UNITED STATES PATENT OFFICE.

WILLIAM K. ANDREW, OF MILWAUKEE, WISCONSIN.

GOVERNOR.

1,405,178.

Specification of Letters Patent. Patented Jan. 31, 1922.

Application filed October 27, 1920. Serial No. 420,045.

To all whom it may concern:

Be it known that I, WILLIAM K. ANDREW, a citizen of the United States, residing at Milwaukee, county of Milwaukee, and State 5 of Wisconsin, have invented new and useful Improvements in Governors, of which the following is a specification.

This invention relates to governors and is particularly adapted to a combined governor 10 and timer.

Objects of this invention are to provide a governor in which friction is greatly reduced; in which the spring pressure against which the centrifugal means operate is not 15 transmitted to the bearings; in which the centrifugal force and spring pressure are balanced against each other within a unitary structure which revolves as a whole; and in which the movable or adjusting member 20 transmits only such force as is required to operate the controlling mechanism.

Other objects are to provide a governor and timer which are self-contained; which occupy a small amount of space; which may 25 be readily manufactured; and which are efficient in operation.

In general, this invention has all of the objects of my co-pending application, Serial 30 No. 373258, filed April 12, 1920, for governors and is an improvement thereover.

In the drawings:

Fig. 1 is a longitudinal sectional view through the combined governor and timer.

Fig. 2 is a corresponding view taken at 35 right angles to the plane on which Fig. 1 was taken.

Fig. 3 is a section on the line 3—3 of Fig. 1.

Fig. 4 is a section on the line 4—4 of 40 Fig. 1.

The device comprises a casing 1 which is arranged to have its brackets 2 bolted to any suitable part of the machine. The casing 1 has an outwardly extending cylindrical projection 3 in which the governor shaft 5 is adapted to rotate, such shaft being supported adjacent its outer end by ball-bearings 6. If desired the space 4 may be provided with a bushing, in an obvious manner, 45 in which the shaft 5 is adapted to rotate. A bevel gear 7 is carried by the outer end of the shaft 5, and meshes with a bevel gear 8 from which the governor receives rotary motion from the engine. The shaft 5 extends upwardly to a point adjacent the top 50 9 of the casing and carries at its upper end

an arm 10. This arm 10 carries a roller 11 arranged to travel around an insulating ring 12 and to be pressed against the inner periphery of such ring. At suitable intervals, contact members 13 are formed in this ring and are connected with binding posts 14 upon the outside of the casing, such connection, of course, and contact members, being thoroughly insulated from the casing. 60 65

The casing 15 which houses this timer and a portion of the main mechanism is of reduced diameter and is adapted to be secured to the lower casing 1. It is provided with an inwardly projecting annular portion 16 70 in which ball-bearings 17 are mounted to properly guide the upper end of the shaft 5. It is to be noted that the stationary portion of the ball-bearings rests upon an annular shoulder 18 formed in the member 16 and 75 thereby serves to support the shaft, the rotary portion of the ball-bearings contacting with a nut 19 threaded upon the shaft 5. This nut 19 is also pinned to the shaft by means of a pin 20 which passes through a 80 corresponding notch in the nut 19.

Above this nut 19 is positioned a second nut 21 which is threaded upon the shaft 5 and it is arranged to be rotated with reference to nut 19 and to properly position the 85 timer by means of projecting lugs 22 formed upon the nut 21 and extending into corresponding sockets in the hub 23 of the timer arm. After the proper adjustment has been secured, a set screw 24 threaded in the nut 90 21 is screwed downwardly against the nut 19 and locks the nut 21 and correspondingly the timer arm in adjusted position. It is to be noted that the timer comprises a relatively 95 stationary member including the insulating ring 12 and the contacts 13, and an adjustable member 21 adapted to be adjusted angularly relatively to the shaft 5 and locked in position by means of a set screw 24 and a movable rotating contacting member 10, 11, 100 12 and 23 removably carried by means of the co-operating lugs and sockets 22 in adjusted angular relation to the shaft 5. By this means a worn timer roller may be quickly removed, and a new timer roller substituted 105 therefor without changing the adjustment. In actual practice this removal and replacement occupies less than one minute, whereas in the former practice it has been usual to spend a half hour or more to replace a worn 110 timer part.

The weights or centrifugally actuated

members 25, 25 are positioned upon opposite sides of the shaft 5 and are pivotally mounted at 26 in the revolving frame 27 pinned at 28 to the shaft 5. These members 25 are shaped as though they were small sections of a cylinder so that they may occupy a small amount of space and may surround other mechanism located in between them. The lower portion of each of these weights 10 is formed with an integral bell crank arm 29 which may be conveniently arranged at an angle to the pivot 26 (see Fig. 4), and are provided with enlargements 30 at their outer ends which are positioned beneath a collar 31 secured upon a sleeve 32 loosely mounted upon the shaft 5. When the weights move outwardly under the action of centrifugal force, the collar 31 and correspondingly the sleeve 32 are moved upwardly. 15

The resilient means for resisting the centrifugal action comprises a spring 33 which surrounds, and is spaced from, the shaft 5. The spring 33 bears at its lower end upon the collar 31 and at its upper end upon the top 34 of an inverted cup-shaped ring 35 loosely mounted upon the sleeve 32. The lower portion of this cup-shaped member is provided with an outwardly projecting flange 36 which engages under a transversely extending rectangular plate 37, the central portion of which is provided with an orifice through which the body of the cup-shaped member 35 projects, and the outer portion 30 of which is provided with a pair of ears 37. A second correspondingly shaped rectangular plate 38 is provided above the plate 37 and has downwardly extending arms 39 which are secured to the revolving frame 27 40 and supported thereby and form guides for the ears 37 which extend upon opposite sides thereof. Between the plates 37 and 38 and in contact with the plate 38 is mounted a rectangular member 40 having a flat upper 45 surface and a slanting lower surface provided with a plurality of grooves 41. Rollers 42 are positioned between the plate 37 and the member 40 and are adapted to seat in and be retained by the grooves 41. Thus when 50 the rollers 42 are moved outwardly, the plate 37 is spaced a greater distance from the member 40 and correspondingly from the plate 38. As such plate 38 is carried by the revolving frame 27 and is stationary 55 relatively to the collar 31, the spring 33 is compressed as the plate 37 is forced away from the plate 38. Also as the rollers 42 seat and are retained in the grooves 41, the force from the spring is not transmitted outwardly from this unitary structure comprising the plates 37, 38 and frame 27, but is internally borne. 60

Means for forcing the rollers 42 apart 65 comprise a pair of arms 43 in whose outer ends the rollers 42 are journaled, pivotally

mounted at 44 upon a collar 45 slidably mounted upon the shaft 5. This collar 45 has a groove 46 formed above the pivot point 44. Into this groove, a pair of rollers 47 extend, such rollers being carried by a fork lever 48 rigidly fastened upon a rock shaft 49. The rock shaft 49 extends outwardly from the casing and is provided with an adjusting lever 50 having a handle 51 (see Fig. 2). This lever may be provided with means for engaging a series of notches 52 formed in a stationary portion 53 of the casing 1 and may also have a speed indicating dial associated therewith to indicate the speed corresponding to any particular setting of the lever 50. When the lever 50 is moved, the shaft 49 is rotated and, through the medium of the forked arm 48, rollers 47, and sliding collar 45, serves to alter the position of the pivot point along the shaft 5. As the pivot point 44 moves towards one end of the shaft, the rollers 42 are either forced apart or drawn towards each other, thereby altering the distance between the plates 37 and 38 and correspondingly altering the tension of the spring 33. After the rollers 42 have snapped into the grooves at which they are located, the effect of the spring 33 is not transmitted outwardly to other portions of the mechanism. 95

The slideable sleeve 32 has threaded to its upper portion a collar 53 provided with a groove 54. A forked arm 55 rigidly mounted upon a shaft 56 carries a pair of rollers 57 at its free end which project into the groove 54 and serve to rock the arm 55 and correspondingly the shaft 56 as the sleeve 32 moves upwardly or downwardly under the influence of the centrifugal members 25. The shaft 56 extends through the casing and its outer end has rigidly mounted thereon a lever 58 which is connected by suitable link mechanism with the control valve of the engine. 100

If it is desired, the entire mechanism may 110 run in oil as the casing is oil-tight. A suitable filling valve 59 being provided adjacent one end thereof. It will thus be seen that a combined timer and governor has been produced which is simple in construction, easily 115 manufactured, and compact.

Also it will be noted that the internal stresses occasioned by the centrifugal force and the force of the spring are borne in a unitary structure and are not transmitted 120 to any of the bearings or sliding contacts.

I claim:

1: A centrifugal governor comprising a shaft, centrifugal means mounted upon said shaft, a frame carried by said shaft and arranged to rotate therewith, a sleeve mounted upon said shaft, means connecting said sleeve and centrifugally actuated means to slide said sleeve upon said shaft, a pair of members, one of which is rigidly connected 125

130

with said frame, and the other slidably mounted in relation thereto, and a spring tending to force said sleeve in one direction and to force said pair of members together and means free to rotate with said frame for spacing and locking said pair of members apart to alter the tension of said spring.

2. A centrifugal governor comprising a shaft, centrifugal means mounted upon said shaft, a frame carried by said shaft for rotation therewith, a sleeve mounted upon said shaft, means connecting said sleeve and centrifugally actuated means to slide said sleeve upon said shaft in response to motion of said centrifugally actuated means, a pair of members, one of which is rigidly connected with said frame and the other slidably mounted in relation thereto, and a spring tending to force said sleeve in one direction and to force said pair of members together, and means for spacing said pair of members apart to alter the stress of said spring, said means so arranged that it will lock in any one of a plurality of positions of adjustment, without producing external stresses.

3. A centrifugal governor comprising a shaft, a frame rigidly mounted thereon, centrifugal means pivotally carried by said frame, a sleeve mounted upon said shaft and arranged to slide thereon under the influence of said centrifugal means, a spring acting in opposition to said centrifugal means, one end of said spring being operatively connected with said sleeve and the other end carried in an adjustably mounted

member, means rotating with and operatively bearing against said frame and adapted to alter the pressure of said spring, whereby centrifugal forces and spring 40 stresses are wholly internally borne by said frame.

4. A governor comprising a main shaft, centrifugally mounted mechanism upon said shaft adapted to be driven thereby, a frame 45 rigidly fastened to said shaft and having a pair of longitudinally extending arms upon which said centrifugally actuated mechanism is pivoted, a sleeve slidably mounted upon said shaft and actuated by said centrifugally actuated mechanism, a spring tending to urge said sleeve in opposition to the operation of said centrifugally actuated mechanism, a wedge-shaped member 50 rigidly associated with said arm, a plate operatively connected with said springs and adapted to move with reference to said shaft, means positioned between said wedge-shaped member and said plate for varying the tension of said spring, said last mentioned means cooperating with said wedge-shaped member to secure positive locking in any position of adjustment, whereby stresses of said spring and of said centrifugally actuated mechanism are wholly internally 55 borne by said frame.

In testimony whereof I affix my signature in the presence of two witnesses.

WILLIAM K. ANDREW.
